United States Patent Office.

JEAN F. BADOYE, OF NEW YORK, N. Y.

Letters Patent No. 70,066, dated October 22, 1867.

IMPROVEMENT IN HAT-FELTING MACHINES.

The Schedule referred to in these Letters Patent and making part of the same.

TO ALL WHOM IT MAY CONCERN:

Be it known that I, JEAN FRANCOIS BADOYE, of the city and State of New York, have invented, made, and applied to use a certain new and useful Improvement in Machinery for Felting Hats; and I do hereby declare the following to be a full, clear, and exact description of the said invention, reference being had to the annexed drawing, making part of this specification, wherein—

Figure 1 is an elevation of my machine, and

Figure 2 is a cross-section of the same at line *z z* of fig. 1.

Similar letters denote the same parts.

The object of my invention is to felt the hat bodies in hot water by machinery, instead of by hand in the usual manner.

My invention consists in a swinging-worker or "hand," that is fitted to press upon and work the felt hat bodies while rolled up, in a manner similar to the hand process. I construct the worker so that it swings on a rock-shaft above, and pendulous arms and weights aid in maintaining the motion, and the hot-water kettle and its inclined sides are so formed, in connection with the worker, that as the worker rolls over the roll containing the hat bodies it rises as the roll passes away from the hot water, producing an increased pressure and squeezing operation that felts the hats similarly to the hand process.

In the drawing *a* is a frame, of suitable size and strength; *b* is a hot-water kettle, of any desired or usual character, heated by fire or steam; *c c* are the inclined sides, extending from the kettle to the edge of the machine. The portions of said inclines that come over the kettle are formed of metal plates *d d*, leaving openings between their edges and the bar *e*, running lengthwise through between the plates *d d*. The rock-shaft *f* is hung in journal-boxes in the frame *a*, and provided with pendulous arms *g*, with weights at their ends. The movement is limited by stops *h*, so that the rock-shaft cannot be turned too far. Through the rock-shaft are mortises receiving the sliding-arms *k*, to the lower ends of which the workers *l* are attached. *m* is a cross-bar extending from one pendulous arm, *g*, to the other, and passing through elongated mortises in the arms *k*, so as to allow of their being raised with the workers *l* to introduce the goods to be felted.

The sheets of felt or hat bodies are folded up of a size adapted to the machine, and are either rolled up alone or upon a wooden or India-rubber roller, care being taken to cross the pieces of felt, so that the direction in which the fibres are laid shall vary, and this is to be borne in mind every time the material is changed between the respective felting operations, the same as in felting by hand. The material to be felted is to be rolled up with a coarse cloth, and properly tied, and placed in the machine under the worker, which is to be lowered, and weighted with sufficient weight in its box-shaped upper surface to give the required pressure. As the worker is vibrated by hand, or other power applied to the pendulous arms or rock-shaft, the roll *t* of the material to be felted is rolled up first one incline and then the other, the water being alternately expelled and imbibed, and the felting operation is performed similarly to the hand process, but much more rapidly and uniformly, in consequence of the hand or worker acting upon the entire surface of the roller, and rising and falling by the arms *k* sliding through the mortises in the rock-shaft *f*.

Several of these workers may be mounted on one rock-shaft in a row over a long kettle.

What I claim, and desire to secure by Letters Patent, is—

The workers *l*, mounted on arms that pass through mortises in the rock-shaft *f*, in combination with the kettle *b* and inclines, for operating in the manner specified upon a roll containing the materials to be felted.

In witness whereof I have hereunto set my signature this seventeenth day of January, 1867.

J. F. BADOYE.
